US0D1080893S

(12) **United States Design Patent** (10) **Patent No.:** **US D1,080,893 S**
(45) **Date of Patent:** **** Jun. 24, 2025**

(54) **MUSCLE STIMULATOR**

(71) Applicant: **HAIKOU LILI INVESTMENT CO., LTD.**, Haikou (CN)

(72) Inventor: **Junyuan Chen**, Haikou (CN)

(73) Assignee: **HAIKOU LILI INVESTMENT CO., LTD.**, Haikou (CN)

(**) Term: **15 Years**

(21) Appl. No.: **29/941,096**

(22) Filed: **May 8, 2024**

(30) **Foreign Application Priority Data**

Apr. 28, 2024 (CN) 202430247781.9

(51) **LOC (15) Cl.** **24-01**

(52) **U.S. Cl.**

USPC **D24/200**; D24/215

(58) **Field of Classification Search**

USPC D13/158, 168; D24/144, 170, 187, 188, D24/200, 214, 215, 231

CPC A61H 2023/0209; A61H 23/0218; A61H 2201/10; A61H 23/00; A61H 23/06

(57) **CLAIM**

The ornamental design for a muscle stimulator as shown and described.

DESCRIPTION

FIG. 1 is a perspective view of a muscle stimulator showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of portion 9 shown in FIG. 3. The dash-dash broken lines in the drawings depict portions of the muscle stimulator that form no part of the claimed design. the dot-dash broken lines in FIGS. 3 and 9 represent boundaries of the enlarged portion and form no part of the claimed design.

1 Claim, 9 Drawing Sheets
